UNITED STATES PATENT OFFICE.

WILLIAM LOEB, OF PROVIDENCE, RHODE ISLAND.

DESIGN FOR A RING, BRACELET, PIN, BUTTON, OR SIMILAR ARTICLE OF JEWELRY.

47,163.

Specification for Design.

Patented Mar. 30, 1915.

Application filed April 13, 1914. Serial No. 831,646. Term of patent 7 years.

To all whom it may concern:

Be it known that I, WILLIAM LOEB, a citizen of the United States, residing in the city and county of Providence, State of Rhode Island, have invented a new, original, and ornamental Design for a Ring, Bracelet, Pin, Button, or Similar Article of Jewelry, of which the following is a specification, reference being had to the accompanying drawing, forming part thereof.

The figure is an edge view of a ring illustrating my new design.

I claim:

The ornamental design for a ring, bracelet, pin, button or similar article of jewelry, as shown.

WILLIAM LOEB.
